QUICK RELEASE MECHANISM

James William Apgar, Havre de Grace, Md., assignor to the United States of America as represented by the Secretary of the Army

Filed Jan. 16, 1962, Ser. No. 166,726

2 Claims. (Cl. 73—12)

(Granted under Title 35, U.S. Code (1952), sec. 266)

The invention described herein may be manufactured and used by or for the Government for governmental purposes without the payment to me of any royalty thereon.

This invention relates to a quick release mechanism and more particularly to a mechanism for dropping large items from various heights in order to study the effects of the falls thereon.

The present invention employs a rectangular frame resting on a hydraulic lifting means which in turn rests on a support at the desired height for the test. A U-shaped member is secured to the frame by a single bolt and the item to be tested is suspended from the U-shaped member. The hydraulic member will lift the frame until the bolt is fractured, thus permitting the specimen to fall.

It is a primary object of this invention to provide a mechanism for quickly releasing an object whereby it will be subjected to a fall of predetermined height for purposes of determining the effects of such fall on the object.

It is another object to provide a quick release device in which the parts can be used repeatedly and with replacement of a single bolt.

A further object is to provide a quick release mechanism that is both quickly assembled for use and economical in construction.

The specific nature of the invention as well as other objects and advantages thereof will clearly appear from a description of a preferred embodiment as shown in the accompanying drawings in which:

FIGURE 1 is a front elevation of the quick release mechanism as assembled for use;

FIGURE 2 is a side elevation of the quick release mechanism;

FIGURE 3 is a sectional detail view taken along lines 3—3 of FIGURE 1, and,

FIGURE 4 is a sectional detail view taken along lines 4—4 of FIGURE 2.

Referring now to the drawings in which reference character 1 represents the quick release device of the invention generally, a support 2, such as an I-beam, is used for mounting the mechanism thereon at a desired height from the ground.

A hydraulic means 3 is rested on top of the support 2, and may be of any type hydraulic jack which can be expediently used.

A rectangular frame, indicated generally by 4, consists of a rectangular upper plate 5. A rectangular lower plate 6 is secured in spaced relation by threaded rods 7 and nuts 8 and is best viewed in FIGURE 2.

Plate 5 rests on hydraulic means 3, while plate 6 is disposed under support 2.

A U-shaped member 9 is provided with a transverse bar 10 for a purpose to be later apparent.

As seen in FIGURE 3, a bolt 11 is passed through

2

smooth bores 12 in plate 6 and 12a in bar 10. Bolt 11 is provided with a head 13 which normally rests on top of plate 6 and secures U-shaped member 9 against the bottom of support 2 by a nut 14.

5 An item to be drop tested is indicated by 15 and may be suspended from the mechanism 1 by a cable 16 passing over U-shaped member 9.

Cable 16 may be connected by link 17 to an ear 18 on specimen 15 and the other end of cable 16 can be fastened to a hook 19 which is hooked quickly to an ear 20 on specimen 15.

Other means for the suspension of the specimen 15 from the U-shaped member 9 may be employed and the aforesaid method is described by way of example only.

15 In operation, the item to be tested, 15, is not always attached to the same support, 2. Various stationary structures can be used depending upon the height needed to perform the test. After selecting the support to be used, the item to be tested is raised by expedient means and is 20 suspended from the U-shaped member 9 which has been attached to frame 4.

The hydraulic means 3 is activated to raise the frame 4 and the lifting action is continued until the upper ends of U-shaped member 9 make firm contact with the under 25 side of support 2. At this point, minor adjustments in height, test item position, etc., are made.

To effect quick release of test item 15, the hydraulic means 3 is caused to apply further pressure to plate 5. This upwardly directed pressure is transmitted by rods 7

30 to plate 6 and to head 13 of bolt 11, down bolt 11 to nut 14, from nut 14 to transverse bar 10, from bar 10 to U-shaped member 9 which is prevented from upward movement by support 2. As hydraulic means 3 continues to apply increased pressure, bolt 11 is snapped and test item 35 15 falls to the ground.

In practice, a retaining means such as a chain (not shown) may be attached to U-shaped member 9 and support 2, or frame 4 to prevent the U-shaped member 9 from falling on the test item 15.

40 It is therefore apparent that a highly efficient means for the quick release of heavy items to be drop tested has been devised and one that involves but little expense in operation.

45 Variations and modifications may be effected without departing from the scope of the novel concept of the present invention as set forth in the appended claims.

What is claimed is:

1. Quick release drop testing apparatus comprising a first 50 support, lifting means on said first support, a frame connected to the lifting means to be raised thereby, second support means with an operative connection to the frame and connectable to an object to be drop tested whereby the lifting means lifts the frame and second support means, the second support means contacting the first support to limit movement of the second support means, the operative connection being frangible upon application of adequate force by the lifting means, whereby the lifting means will lift the frame and second support means until the

55 second support contacts the first support and continued lifting will rupture the frangible operative connection thereby permitting the second support, and any object which may be connected thereto, to fall free of the other apparatus.

2. A quick release drop testing machine including in combination, a support and a lifting means normally resting on the upper side of said support, a rectangular frame comprising an upper plate resting on said lifting means and being disposed normal to said support, a lower plate spaced below said support, a pair of rods secured, one each, to the ends of said upper and lower plates, said rods maintaining said plates in parallel relation, a U-shaped member having a transverse bar integral thereon, said U-shaped member being disposed below said support, and

a bolt connecting to said transverse bar and said lower plate whereby when said frame is lifted by said lifting means, said U-shaped member will contact the under side of said support and upon continued lifting of said frame by said lifting means, said bolt will be fractured to permit said U-shaped member to drop.
